SEALING DEVICE FOR CENTRIFUGAL PUMPS

Anthony L. McHugh, Easton, Pa., assignor to
 Ingersoll-Rand Company, Jersey City, N. J., a
 corporation of New Jersey

Application August 7, 1935, Serial No. 35,081

3 Claims. (Cl. 103—111)

This invention relates to improvements in centrifugal pumps and more particularly to a sealing device for vertically split centrifugal pumps whereby a flexible seal is provided between the shell or casing of the pump and the stator parts thereof.

Vertically split pumps are commonly constructed with a cylindrical casing or shell or barrel adapted to have its ends closed by heads in which an impeller shaft may be journaled. The rotor parts are assembled upon the shaft in any conventional manner and the stator or diaphragm is made up of a series of annular segments adapted to be held tightly against each other to form diffusers or stage connections between the outlet of one impeller and the inlet of another. Such pumps are often used for pumping fluids of relatively high or low temperatures such as hot oil, boiler feed water or brine, the temperature effect of which is more pronounced upon the pump mechanism than upon the barrel or casing so that there will be a greater expansion or contraction (as the case may be) of the former than the latter. This differential expansion is likely to break any non-resilient seal and open leakage points between the barrel or casing and its head or closure. It is an object of this invention to provide a flexible seal of simple and inexpensive construction which may be readily applied to a pump of the type described and which will furnish a pressure tight and effective seal under all conditions of temperature and pressure.

Other objects are either apparent or will be set forth hereinafter.

In the accompanying drawings, Fig. 1 represents a longitudinal view partly in section of a centrifugal pump to which the invention has been applied.

Fig. 2 is a view taken upon the lines 2—2 of Fig. 1 and looking in the direction of the arrows in which the invention is further illustrated, and Fig. 3 is an enlarged sectional view illustrating the detail of one part of Fig. 1, and

Fig. 4 is an enlarged sectional view showing a modification of the invention.

Referring to the drawings in which similar reference characters denote similar parts, a casing or barrel 10 is closed at each end by heads 12. A suitable inlet 14 is provided in one head and a similar outlet 16 is provided in the other. The heads may be conveniently fixed to the barrel by bolts 18. Journaled in suitable bearings in the heads (which bearings are not more particularly described because they are not an essential feature of the invention) is a shaft 20 upon which are

mounted, by suitable means such as keys and keyways 40, a pair of impellers including a low pressure impeller 24 and a high pressure impeller 26.

The diffuser passages between the first stage impeller 24 and the second stage impeller 26 and between the second stage impeller 26 and the outlet 16 are formed in diaphragm segments 28, 30 and 32, these segments being annular members which are assembled within the barrel 10 to form the diaphragm or stator of the centrifugal pump. 16

The elements 30 and 32 are held together by means of a bolt 36 having a hollow head in which a spring 38 may be inserted. Clamped between the elements 30 and 32 is a flexible metallic member in the form of an annular gasket 34 the inner edge of which is held firmly between the members 30 and 32. The outer edge of the gasket 34 is clamped between the barrel 10 and its head 12 by means of the bolts 18. The central portion of the gasket 34 is unsupported, being freed from contact with the segments 30 and 32 because of a bevel provided at the periphery of the segments 30 and 32. It will be seen from this construction that upon elongation of the stator elements under the influence of heat the flexible gasket 34 may bend slightly to the left and upon contraction or shortening owing to the effects of low temperature the gasket 34 may bend to the right, but at all times a complete seal is made between the diaphragm segments and the barrel and head. 80

In the modification illustrated by Fig. 4 the seal is shown at the inlet end of the pump and differs in form, though not in principle, from the type just described. The impeller 24 discharges into a diffuser passage 25 formed in a diaphragm segment 28'. The barrel or shell 10 is provided with a shoulder 50 against which a washer 52 may be fitted. In the head 12 is an annular recess 54 in which an annular flange 56 of a metallic gasket 58 may be pressed. 40

The gasket 58 in this instance is in the form of an annular plate having a heavy flange 56 at its inner edge and a lighter flange or shoulder 60 near its periphery. That part of the plate outside of the shoulder 60 is pinched between the diaphragm segment 28' and the shoulder 50 on the barrel 10, the flange 60 overlapping the joint between the washer 52 and the shoulder 50. Intermediate the flanges 60 and 56 the plate 58 is dished as clearly appears in the drawings. The tendency of the deflected or dished portion to flatten out exerts pressure against the flanges 56 and 60, and the latter is urged firmly against the washer 52 and the shoulder 50 of the barrel 10. The deflection of the intermediate part of the 55

plate 58 provides a resilient seal which can accommodate itself to relative movement between the cylinder and the diaphragm of the pump.

In order to provide space for the shoulder 60 5 and the deflection of the dished portion of the plate 58 a depression 62 is formed in the head 12.

In the diaphragm segment 28' a series of bores 64 act as seats for springs 66 which exert pressure against an annular ring 68. This ring bears 10 upon the inner part of the gasket 58 and urges the inner shoulder 56 into the recess 54.

As an additional seal, although adding nothing 15 to the flexibility of the assembly, the inner edge of the gasket 58 may be welded to the head 12 as shown at 70.

By either of these simple and inexpensive devices I have provided a seal which is efficient in 20 making a pressure tight joint at the head of a centrifugal pump, but at the same time providing sufficient flexibility to take care of any reasonable 25 expansion or contraction due to high or low temperatures.

Having thus disclosed my invention I do not desire to be limited to the exact disclosure, but 25 claim:

1. In a centrifugal pump of the type described, a cylinder, a pair of heads therefor, a plurality of segments forming a diaphragm assembled in the cylinder, an annular flexible sealing member at

the periphery of the diaphragm and positioned between the diaphragm and the cylinder and one of its heads, and means firmly securing the outside and inside portions of the sealing member, but leaving the intermediate portion free to flex under relative expansion and contraction of the diaphragm and the cylinder. 5

2. A centrifugal pump comprising a cylinder, heads for each end thereof, a plurality of diaphragm elements assembled in the cylinder and 10 an annular gasket of flexible material having its inner edge clamped between two of the diaphragm elements and its outer edge clamped between one end of the cylinder and one head to form a seal for the discharge end of the pump and to 15 permit limited movement of the diaphragm elements with respect to the cylinder.

3. In a centrifugal pump of the type described, a cylinder, a pair of heads therefor, a plurality of diaphragm elements assembled therein, an annular gasket of flexible material to seal the discharge end of the pump, means to clamp the outer edge of the gasket between the cylinder and one of the heads, and means to clamp the inner edge 20 between two of the diaphragm elements to permit relative movement between the cylinder and the diaphragm.

ANTHONY L. McHUGH.
